CLAIM

The ornamental design for foldable front cover for electronic device, as shown and described.

DESCRIPTION

FIG. 1 is a front perspective view of a foldable front cover for electronic device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and

FIG. 8 is a perspective view thereof shown folded into a stand for supporting an electronic device; and,

FIG. 9 is a perspective view thereof shown folded into another stand for supporting an electronic device.

The broken lines represent an environment of use and form no part of the claimed design.

1 Claim, 9 Drawing Sheets
